MULTICOLOR PRINTING PRESS

Filed Oct. 31, 1924

Inventor:
Frank P. Campbell,

John H. M. Kelly

UNITED STATES PATENT OFFICE.

FRANK P. CAMPBELL, OF TUXEDO, MARYLAND.

MULTICOLOR PRINTING PRESS.

Application filed October 31, 1924. Serial No. 747,085.

To all whom it may concern:

Be it known that I, FRANK P. CAMPBELL, a citizen of the United States, residing at Tuxedo, in the county of Prince Georges 5 and State of Maryland, have invented certain new and useful Improvements in Multicolor Printing Presses, of which the following is a specification.

My said invention relates to a multi-color printing press and it is an object of the same to provide improved means whereby color printing in a variety of colors may be performed rapidly and at the same time in an efficient and comparatively inexpensive 15 manner and without removing the sheet from the impression cylinder or other instrumentality on which it is held during the printing operation.

Referring to the accompanying drawings 20 which are made a part hereof and on which similar reference characters indicate similar parts,

Figure 1 is a plan view of one embodiment of my invention, 25 Figure 2, a side elevation of the same, and Figure 3, a detail view of certain parts. In the drawings reference character 10 indicates the frame of the machine, said frame including a groove or way for a 30 sprocket or chain belt 11 passing about four sprockets 12 of which one is indicated as a driving device for the chain and the others may be plain guide rollers if desired.

The driving sprocket is operated by a 35 shaft 13 having at each end a beveled pinion, one of which engages a pinion on the shaft of the sprocket 12 and the other a pinion on a main driving shaft 14 provided with fast and loose pulleys 15 and 16 over 40 which a belt 17 passes, the belt at the other end passing over pulleys on the shaft of a motor 18 by which the machine is driven.

At a distance from the pulleys 15 and 16 on the shaft 14 I have provided a spur gear 45 19 meshing with a spur gear 20 which drives the impression cylinder 21. Said impression cylinder has gear teeth 22 at opposite ends adapted to mesh with the teeth of racks on type frames as hereinafter described.

A table 23 for paper 24 is provided as 50 usual at one side of the impression cylinder and a receiving table 25 is provided at the other side. Any conventional or desirable holding means may be provided on the cylinder and stripper fingers 26 serve as

usual for lifting the sheet off the cylinder. The details of the mechanism employed for these purposes are well understood, being of any appropriate form and require no special description. 60

The chain belt 11 has attached thereto at intervals sliding tables 27 which move about the top of the frame in the direction indicated by the arrows. These tables are adapted to have type beds or frames 28 locked in place thereon by quoins 29, these type frames holding set-ups of type 30. As the parts travel from one of the corner positions indicated to another the tables, the type frames and the set-ups will all maintain the same position relative to one another and may be said to be oriented with regard to each other at all times since, e. g. the west side of a frame will remain west in all positions as will be obvious from consideration of the drawing where the term "heading" is shown as set up in type on each of the frames. Figure 1 may, of course, be taken to represent four different positions of the same set-up or four different set-ups. Each of the tables has a set of rack teeth 31 at each of two opposite sides which rack teeth are adapted to mesh with teeth 22 at the ends of the impression cylinder to regulate accurately the position 70 of the set up relative to the face of the impression cylinder and insure that each of the successive set-ups shall be applied in exactly correct position with reference to the others. 80

At points approximately midway the length of the sides of the machine frame there are located ink fountains 32, mounted on vertically reciprocating frames 50, each intended to receive ink of different color 95 or character from the others, which ink may be applied to the type beds or set-ups by means of a series of rollers 33, 34, 35 and 36, also carried by said frame 50, or by any other conventional or desirable means. To insure that the same kind or color of ink will be applied to a set-up at each passage of the bed or set-up past its respective ink fountain I have provided means comprising 100 a series of cams 37 upon which rest rollers 51 on the lower end of frame 50, and driving means therefor each arranged to engage with the roller 51 of the frame 50 of the particular inking arrangement to engage the type of the appropriate bed for 105 110

inking the same. The driving means for said cam comprises a chain belt 38 driven by a pulley on the shaft 14 and driving a pulley on a shaft 39. At the opposite end 5 of said shaft from the cam 37 is a beveled gear driving through a meshing beveled gear, a camshaft 40 for bringing the proper inking device into operative relation with the second bed or set-up. The shaft 39 is 10 shown as carrying a spur gear 41 meshing with a spur gear 42 on a shaft 43 which is the third cam shaft of the series and cooperates with related parts to bring the third inking device into operative relation 15 with the third bed or set-up. At the opposite end of the cam shaft 43 is a beveled gear meshing with a beveled gear on a shaft 44 which is the fourth cam shaft and operates in connection with the fourth bed or 20 set-up.

The cylinder 21 is operated on the well-known "stop cylinder" principle, that is it has an intermittent movement, or a short stop after each revolution, or between the 25 printing of different colors, so as to afford opportunity for removing the printed sheets and placing sheets to be printed in position. It will be understood, of course, that when the machine first starts the cylinder will 30 make four revolutions before the printing of the first sheet is completed and therefore that the second sheet will not be fed to the machine until the four revolutions and the printing of four colors have been completed. 35 While any appropriate mechanism, such as ordinarily employed for like stop cylinder operation in other printing machines, may be employed I have indicated, in Figure 3, an arrangement of mechanism which I deem 40 appropriate. In this arrangement the loose pulley 15 is adapted to be connected by a clutch to the fast pulley 16 on driving shaft 14. Fast pulley 16 is capable of slight longitudinal movement on shaft 14, being 45 mounted thereon by a spline 55. The clutch faces of said respective pulleys are normally held apart, or in non-operative position, by a spring 56 while a roller 58 on the arm of a forked member 57 is adapted to engage 50 the outside face of pulley 15 and at appropriate intervals drop into a notch provided therefor, as shown in Figure 3, which results in the separation of the clutch faces and the momentary stopping of the cylinder 55 for the purpose before stated. The rotation of pulley 15, however, immediately operates to bring roller 58 out of said notch to ride upon the normal outside face of said pulley 15 and thus close the clutch so 60 that shaft 14 will rotate with said pulley 15 until said notch again registers with said roller 58. By this means a short stop or tarry of the cylinder 21 is accomplished at each rotation thereof.

65 It will be seen that my invention contem-

plates the printing of a sheet of paper in a plurality of colors, here indicated as four, without being removed from the cylinder, the mechanism being so arranged that each of the colors will be properly located with 70 respect to the others on the sheet. This results in a great saving of time over previous practice and also gives more accurate results and less waste since the sheet need be fed but once and is not so likely to be damaged in handling and for the further reason that there is less chance of off-sets and spoilage in the actual printing operation. 75

It will be obvious to those skilled in the art that the principles of my invention may 80 be embodied in mechanisms of widely different forms and details of construction and therefore I do not limit myself to the form of the invention shown in the drawings and described in the specification but only as 85 indicated in the appended claims.

Having thus fully described my said invention, what I claim as new and desire to secure by Letters Patent is:

1. In a multi-color printing press a rectangular track, an impression cylinder, a plurality of type frames moving successively past said cylinder on said track, a plurality of sources of ink differing in color, controlling means for causing ink of one color 90 only to be applied to each type frame respectively, and means for causing the type on each frame to act on the paper on the impression cylinder, substantially as set forth.

2. In a multi-color printing press a rectangular track, means for holding a sheet of paper, independent means for holding each of a plurality of set-ups of type, means at different sides of said track to apply ink 100 of different colors to different set-ups, and means to apply said set-ups successively to such a sheet of paper, substantially as set forth.

3. In a multi-color printing press a rectangular track, means for holding a sheet of paper, a series of moving type frames, a plurality of inking means at different sides of the track supplying a characteristic ink to the type on one of said frames, and means for bringing each inking arrangement into operative relation to one set-up, substantially as set forth.

4. In a multi-color printing press, means for holding a sheet of paper, a set of four type-frames facing in the same direction, said frames traveling on an endless track, means for causing them to act successively on such a sheet of paper, and means for applying a distinctive ink to each set-up on each travel round the track, substantially as set forth.

5. In a multi-color printing press an endless track, means for holding a sheet of paper, a set of four type-frames traveling on said track, said type-frames being so 130

guided that the type thereon reads in the same direction at all times, means for causing them to act successively on such a sheet of paper, inking means at spaced intervals along the track, and means for causing operative engagement of an inking arrangement with a specific type frame at each round of the track while preventing operative engagement between said type-
5 frame and the other inking means, substantially as set forth.

6. In a multi-color printing press an endless track, means for holding a sheet of paper, a set of four type-frames, traveling on said endless track said type-frames facing in the same direction at all times, means for causing them to act successively on such a sheet of paper, inking means at spaced intervals along the track, and means for caus-
10 ing operative engagement of an inking

means with a specific type-frame at each round of the track while preventing operative engagement between said inking means and the other type-frames, substantially as set forth.

7. In a multi-color printing press, a rectangular track, type-frames traveling on said track, roller inkers between the corners of the track, a cam adjacent each inker arranged to lower one only of the series of inking arrangements into operative engagement with the respective type-frame, and means for bringing a sheet of paper into operative engagement with successive type frames, substantially as set forth.

In witness whereof I have hereunto set my hand and seal at Washington, District of Columbia this 28th day of October, A. D. nineteen hundred and twenty-four.

FRANK P. CAMPBELL. [L. S.]
